DESIGN FOR A SEWING MACHINE

Norman V. Christensen, Chicago, Ill., assignor to
Union Special Machine Company, Chicago, Ill.,
a corporation of Illinois

Application May 9, 1939, Serial No. 84,889

Term of patent 14 years

To all whom it may concern:

Be it known that I, Norman V. Christensen, a citizen of the United States of America, residing at Chicago, in the county of Cook and State of Illinois, have invented a certain new, original, and ornamental Design for a Sewing Machine, of which the following is a specification, reference being had to the accompanying drawings, forming a part thereof.

Of the drawings:

Fig. I is a perspective view showing one side and end of the machine;

Fig. II is a perspective view showing the opposite side and end of the machine;

Fig. III is a top plan view;

Fig. IV is a perspective view, approaching a side elevation; and

Figs. V and VI are end views.

I claim:

The ornamental design for a sewing machine, as shown.

NORMAN V. CHRISTENSEN.
